UNITED STATES PATENT OFFICE.

AARON FRANCIS STOWE, OF WORCESTER, MASSACHUSETTS, ASSIGNOR TO
A. F. STOWE MANUFACTURING COMPANY, OF WORCESTER, MASSACHU-
SETTS, A CORPORATION OF MASSACHUSETTS.

MACHINE FOR TREATING SHIN OR SHANK LEATHER.

SPECIFICATION forming part of Letters Patent No. 740,709, dated October 6, 1903.

Application filed December 18, 1902. Serial No. 135,670. (No model.)

To all whom it may concern:

Be it known that I, AARON FRANCIS STOWE, a citizen of the United States, residing at Worcester, in the county of Worcester and State of Massachusetts, have invented a new and useful Machine for Treating Shin or Shank Leather, of which the following, together with the accompanying drawings, is a specification sufficiently full, clear, and exact to enable persons skilled in the art to which this invention appertains to make and use the same.

The shank and shin portions of hides which are tanned for sole-leather present an irregular, curled, and ruffled margin, having a hard, stiff, and outwardly-rounded area extending along the central part thereof, rendering the stock of such form and refractory nature that it cannot be worked on machines when put into use without great waste and much trouble and of such character that it is of little value and suitable only for inferior portions of boot and shoe work—such as filling-pieces, under lifts for heels, and other small parts—the curl and hardness of the stock making it difficult to cut with dies and frequently requiring a recutting to get it into proper form.

The object of my present invention is to provide a method of and means for treating or preparing such shank and shin stock and similar hard, curled, or refractory portions of leather, whereby the same may be straightened and rendered comparatively pliable and fit for working into boot and shoe stock of a higher or better class than could be heretofore done—such as insoles, taps, counters, top-lift heelings, &c.—thereby making such leather more valuable and useful in the arts and putting it into a condition to be conveniently and economically worked or subjected to the die-cutting and machine manipulations through which it subsequently has to pass in the processes of boot and shoe manufacture.

Another object is to provide in a machine for the purpose specified an efficient means for bringing the leather into a reversely-curved condition and simultaneously severing or rupturing the under fibers to a degree sufficient to permit the refractory, rounded, or undecurled portions to assume a flattened position, as more fully hereinafter explained.

Another object is to provide, in combination with means for feeding and slitting the hard rounded portion of the shank or shin stock, means for directing and supporting the irregular and ruffled border portions and preventing the same from interference with the proper working of the mechanism while passing through the machine.

Minor objects and features of my invention are disclosed in the following detailed description, the particular subject-matter claimed being definitely set forth in the summary.

I attain these objects by the mechanism illustrated in the accompanying three sheets of drawings, wherein—

Figure 1 represents a vertical central section of a machine embodying my invention. Fig. 2 is a vertical section near the gears at the end of the roller-axes. Fig. 3 is a vertical section through the under-guard plates. Fig. 4 represents a horizontal or plan view of the machine with the top of the frame-jaws shown in section and the adjusting-shaft omitted. Fig. 5 is a horizontal section showing the parts underneath the feed-rolls. Fig. 6 is a horizontal section showing the cutter-roll. Fig. 7 is a fragmentary detail view representing the front of the bed-roll and cutter-roll with the pressure-bars and guard in section. Fig. 8 is a longitudinal vertical section showing the arrangement of the presser-bars, the presser-bar springs, and adjacent devices. Fig. 9 is a transverse section showing the relation of the rolls and presser-bar mechanism. Fig. 10 shows in separate detail the structure of one of the presser-bars.

In the embodiment of my invention as herein illustrated the machine comprises a bed-roll B, front and rear feed-rolls F and E, having roughened or fluted surfaces, a cutter-roll composed of a series of annular disk-cutters C, the edges of which run adjacent to but not in contact with said bed-roll, and a series of presser-bars D, adapted for directing the leather and for holding it against the bed-roll surface while acted upon by the cutters.

The above-named rolls are preferably formed of about two inches diameter and about four inches, more or less, in length.

and provided with long axles *f*, *b*, and *e* of less diameter than the rolls, which axles extend to the right and left for a sufficient distance to accommodate the width of any piece 5 of stock liable to be found among the shin and shank pieces to be treated. The cutter-roll and bed-roll are respectively journaled in bearing-boxes *H* and *G*, mounted in the housing-jaws *a* of the upright end frames *A*.
 10 The bed-roll above the cutter-roll and said bearing-boxes are made adjustable up and down in the jaw-spaces, the lower boxes *H* by a screw-stud and nuts, as at *h*, for seating said lower boxes at proper relative position, while the upper boxes *G* are adjustable 15 by means of the screws *I*, mounted in the jaw-caps *a'* and threaded into the tops of said upper boxes, for giving the temporary adjustment of the bed-roll for varying thicknesses of leather, as desired.
 20

For operating the adjusting-screws of both boxes *G* in unison there may be employed a top shaft *I'*, turning in bearings on the jaw-caps and connected with the screws *I* by 25 beveled gears *i*, said shaft having a hand-wheel *I²*, whereby the journal-boxes can be simultaneously adjusted up or down by rotation of the shaft in well-known manner.
 30

Between the boxes *H* and *G* there is a stud or detent *4*, that serves as a stop to prevent the bed-roll from being moved into contact with the edges of the cutter-blades. The bed-roll and feed-rolls are connected to rotate in unison by intermeshing gears *B²*, *F²*, and 35 *E²*, fixed on their respective axles near the journal-bearings. Said gears may in practice be covered and protected by a suitable guard or housing.
 40

The frame of the machine preferably consists of the upright end portions *A*, rigidly united at the proper height by breast-girths or horizontal supporting members *A'*, that extend across in front and rear of the cutter-shaft *c*. Said girths are best made with a longitudinal groove in their upper side, as indicated, for aid in the support and connection of parts that are mounted thereon.
 45

The feed-roll axles *f* and *e* are respectively journaled in movable bearings mounted in a 50 manner to afford a resilient yielding action of the feed-roll from and toward the bed-roll. For this purpose bearing-brackets *J'* are fixed on the girths or main frame, and the journal-bearings *J* are arranged to slide 55 in said brackets, and suitable resistance-springs *K* are combined therewith, which tend to press the feed-rolls toward the bed-roll at the front and rear thereof.
 60

The circular blades or cutters *C* are mounted 65 as a gang upon their shaft *c* about one-fourth of an inch, more or less, apart and are held in place by intermediate rings and tubes arranged on an axial shaft and tightened by screw-nuts threaded *t*, thereon adjacent to the journals. Said rings, tubes, and nuts, together with the axial portion, when assembled for use constitute the cutter-shaft *c*.

The presser-bars *D* are arranged in a series and extend from front to rear beneath the feed-rolls and bed-rolls, respectively, passing between and adjacent to the several cutter-blades. The top edges of said presser-bars are each formed with projections *2* and *3*, (see Fig. 10,) that stand adjacent to the feed-roll faces and serve to deflect or bend 70 the leather and to direct it around the bed-roll, while that portion of the bar between the points *2* and *3* is formed as at *5* of suitable shape to press the leather against the bed-roll surface at the position opposite the 75 cutters. (See Fig. 9.) The presser-bars are upheld by a yielding support device, which in the present instance consists of a pair of endwise-movable standards *D'*, fitted in openings in the girth *A'* and resting upon upwardly-expanding springs *L*. From the top 80 of one standard to the other there extends a cross bar or rod *d*, upon which the series of presser-bars *D* are mounted, as best shown in Figs. 8 and 9. The presser-bars are preferably arranged to have limited free lateral play upon the cross-bar *d*, thereby obviating any tendency to cramp or bind on the cutters that run between them.
 85

Screws *S*, threaded in the frame and engaging against the heads of the standards *D'*, serve to limit the upward action of the springs *L* and for regulating the closeness of approach of the bars *D* to the bed-roll.
 90

M indicate under guards arranged beneath the roll-axles and which serve for directing the irregular ruffled edges of the leather that extend beyond the ends of the bed and feed rolls proper and for preventing such portions of the leather from interfering 100 with the girths and under mechanism as the stock is run through the machine. Said guards are formed in front and rear sections, each provided with a foot that seats in the groove on the respective girth *A'*, where it is 105 movably retained by a screw *m*, that passes through a slot in the foot, (see Figs. 5 and 8,) the guard-sections being permitted a limited back-and-forth movement and a slight lateral swinging action. Springs *n* are arranged in 110 holes formed in the foot at either side of the screw *m* to press against the wall of the groove, thereby serving to keep the guard-section normally in proper central position. The tops of the guards are provided with ribs 115 *8*, that project upward adjacent to the feed-roll axles for preventing the edges of the leather from passing under said axles. That part of the guard beneath the bed-roll axle is invertedly arched (see Fig. 3) and the front 120 section thereof provided with a plate-flange 125 *9*, that laps over the edge of the rear section, for conducting the leather across the intervening space, the irregular marginal portions of the leather passing into and from between the axles in the direction indicated by arrows on Fig. 3, while the central part of the stock passes between the rolls, as indicated by dotted lines in Fig. 9.
 130

P indicates the operating-shaft, supported to turn in suitable bearings on the rear part of the frame and provided with a pulley P' or other desired means for applying motive power thereto. The cutters C are rotated by means of a gear C², fixed on the end of the cutter-shaft c and meshing with a pinion C³, fixed on the operating-shaft, while the bed-roll is rotated by means of a gear B', fixed on the end of its axle and meshing with an intermediate gear O, that in turn meshes with a pinion B³, fixed on said operating-shaft. The rolls and cutters when in operation rotate in the respective directions indicated in Fig. 9.

The operation of this invention is as follows: The mechanism being in motion, the hard curled portion of the shank or shin piece is inserted endwise, rounding side upmost, between the feed-roll F and bed-roll B and is drawn in by the rotative action of said rolls. The advancing leather is directed under the bed-roll B and up between the bed-roll and rear feed-roll E by means of the presser-bars D and points thereon. The advancing stock is thus caused to assume a laterally-straight and longitudinally-reversed curvature by being bent from its original overrounded condition to an opposite underrounded condition about the bed-roll B, against the surface of which it is held and carried by the feed-rolls. Simultaneously with this reverse curving of the stock the strained under fibers are ruptured or severed for a slight distance into the thickness of the leather by means of the rotating cutters C, forming therein a series of slits or surface grooves at narrow intervals apart as the stock is advanced through the rolls, said grooves running longitudinally of the hard shin area, thus destroying or overcoming the refractory character or tendency of the shin-leather to curl up and rendering it comparatively straight and pliable and in suitable condition for convenient working, thereby increasing the value and utility of such leather to about twice its original value, more or less. As the hard central boss of the shin or shank pieces passes through the rolls the softer ruffled marginal portions are allowed to draw through the spaces between the roll-axes, supported and directed by the under guides, which yield one way or the other to accommodate irregularities that may occur as the stock advances.

The slits or grooves in the under side of the leather are not made of sufficient depth to injure the valuable portion of the material, and the slitted surface may be subsequently split off, since the straightening-out process effected by the action of this improved mechanism will enable the leather to lie flat and to be run through the ordinary leather-splitting machines without probability of destroying it by unequal splitting.

What I claim, and desire to secure by Letters Patent, is—

1. A machine for the purpose specified,

comprising means for reversely curving the leather and for feeding forward or advancing the same in such curved relation, in combination with a gang of blades or cutters arranged for rotatively acting against the convex surface of the curved leather for severing or rupturing the outer fibers while under strain of the curvature, without cutting through the body of the leather.

2. In a machine for treating shin and shank leather, the combination of means for transversely straightening out the normal curvature of the shin or shank portion, and a series of cutters adapted for forming a narrow-spaced series of longitudinal slits or grooves partially but not completely through the leather, simultaneously with the straightening action.

3. In a machine for treating shank and shin pieces of leather, the combination of a bed-roll, front and rear feed-rolls acting in conjunction therewith for curving and advancing the leather about said bed-roll, a cutter-roll comprising a series of blades or cutters disposed opposite said bed-roll, yielding devices for guiding and pressing the leather against said bed-roll, and means for rotating the several rolls and cutters.

4. A machine for treating shin and shank leather, comprising a bed-roll, two feed-rolls respectively acting in conjunction therewith for curving and advancing the leather about said bed-roll, a series of rotating disk cutters adjacently supported on a shaft opposite said bed-roll, a series of presser-bars intermediate to said cutters, springs supporting said presser-bars, means for regulating the distance between the cutter and bed rolls, and means for rotating the series of rolls and cutter-shaft.

5. In a machine for treating shin and shank leather, in combination, a bed-roll, feed-rolls arranged before and after said bed-roll, said rolls provided with extended axles, intermeshing gears connecting the feed-roll and bed-roll axles, laterally-yielding bearings for the feed-roll journals, springs and spring-supporters therefor, a cutter-shaft carrying a gang of circular cutters opposite said bed-roll, yielding presser-bars between said cutters, spring-supports for said presser-bars, and deflecting-guards beneath the roll-axes, for the purpose set forth.

6. In a machine for treating shin and shank leather, the combination, with the cutters, cutter-shaft, bed-roll and feed-rolls for curving and advancing the curled central part of the leather, said rolls provided with extended axles of less diameter than the rolls; of the under guards provided with upwardly-inclined ribs adjacent to the feed-roll axles for deflecting or directing the irregular marginal portions, said guards mounted upon the frame in a manner to have resilient transverse yielding action, substantially as set forth.

7. In a machine of the character described, the combination, with the bed-roll, feed-rolls

and cutter-roll having extended axles, and the frame-girths provided with a groove; of an under-guard member having a foot movably seated within said groove, a retaining stud or screw engaging a slot in said foot, and springs horizontally arranged at either side of the screw and pressing against the foot and outer wall of the groove, for the purpose set forth.

10. 8. In a machine for the purpose specified, the combination, with the bed-roll, feed-rolls at front and rear of said bed-roll, and the cutter-roll comprising a gang of circular cutter-blades; a series of presser-bars severally provided with lugs or points that project upward adjacent to the feed-roll faces, substantially as and for the purpose set forth.

9. In a machine for the purpose specified, in combination, with the gang of circular rotatable cutters, the bed-roll and feed-rolls; the series of presser-bars severally disposed beneath said bed-roll and feed-rolls and between the cutters, cross-rods carrying the ends of said presser-bars, supporting-stands movably fitted in guide-openings in the breast-girth and sustaining the respective ends of said cross-rods, lifting-springs for elevating said standards and presser-bars, and adjustable stops or screws that limit the upward movement thereof, substantially as set forth.

10. In a machine for the purpose specified, the combination, of the frame provided with housing-jaws, the cutter-shaft mounted in

bearing-boxes supported in said jaws, a narrow-spaced series of circular cutters on said shaft, the bed-roll mounted in bearings adjustably supported in said jaws, adjusting-screws journaled in the jaw-caps and threaded into said bearings, means for simultaneously operating said screws, and a stop device limiting the approach of said bed-roll bearings to the cutter-shaft bearings.

11. In a machine for the purpose specified, the combination of the end frames provided with housing-jaws, the bed-roll and cutter-shaft severally mounted in bearing-boxes supported in said jaws, means for adjusting or regulating the position of said bearing-boxes, the feed-rolls acting against the front and rear of said bed-roll, laterally-yieldable bearings for the feed-roll journals, bearing guide-brackets therefor fixed to the frame, springs arranged in said brackets for pressing the feed-roll toward said bed-roll, gears connecting the roll-axes, a gang of circular cutters on said cutter-shaft, a series of yielding-supported presser-bars extending across the space beneath said bed-roll and feed-rolls between the circular cutters, substantially as set forth.

Witness my hand this 16th day of December, 1902.
